Primary Examiner — Susan Bennett Hattan(74) *Attorney, Agent, or Firm* — Melissa G. Krasovec; Leonard W. Lewis; Steven W. Miller(57) **CLAIM**

The ornamental design for a cap, as shown and described.

DESCRIPTION

FIG. 1 is an upper perspective view of a cap;
 FIG. 2 is a lower perspective view thereof;
 FIG. 3 is a top view thereof;
 FIG. 4 is a bottom view thereof;
 FIG. 5 is a front view thereof;
 FIG. 6 is a right view thereof; and,
 FIG. 7 is a left view thereof.
 The broken lines in the drawings depict environmental subject matter only and form no part of the claimed design.
